UNITED STATES PATENT OFFICE.

BERT LANGLEY, OF GRANTWOOD, NEW JERSEY.

APPARATUS FOR FEEDING ENVELOPS.

1,196,706.

Specification of Letters Patent. Patented Aug. 29, 1916.

Application filed January 25, 1913. Serial No. 744,114.

To all whom it may concern:

Be it known that I, BERT LANGLEY, a citizen of the United States of America, residing in Grantwood, county of Bergen, and 5 State of New Jersey, have invented a certain new and useful Apparatus for Feeding Envelops, of which the following is a specification.

This invention relates to automatic feeding devices for sheets, cards, envelopes and the like, with particular reference to that 10 type of mechanism in which the feeding is done sheet by sheet from a stack or pile.

One object of the invention is to provide 15 a simple and efficient mechanism which will deliver automatically single sheets or envelopes from a stack or pile, for whatever purpose such delivery may be required.

Another object is to adapt such a mechanism 20 for use with a typewriter for the automatic feeding of envelopes, cards and the like into the typewriter carriage.

Another object is to provide such a typewriter attachment with means to permit an 25 easy and rapid movement of the device into and out of operative position.

Another object is so to combine the attachment with the typewriter that the normal and easy operation of the latter will not 30 be affected in any way; and still other objects will appear in the following description and claims.

In the drawings, Figure 1 is a front elevation of the device as mounted upon a typewriter; Fig. 2 is a side elevation, partly in 35 section, along the line 2—2 of Fig. 1; Fig. 3 is a front elevation showing a partly completed movement of the mechanism; Fig. 4 is a sectional plan taken through the line 40 4—4 of Fig. 3; Fig. 5 is a front elevation showing the mechanism at one limit of its movement; Fig. 6 is a side elevation showing 45 a tilting arrangement; Fig. 7 is a front elevation of the device when in a tilted or inoperative position; Figs. 8, 9 and 10 illustrate the various phases of the feeding 50 movement; Figs. 11 and 12 are detail views showing the application to the feeding plunger of detachable needle points designed to engage and cause the successive feeding of 55 cards; Fig. 13 is a perspective view of an angular plate detachably secured to the floor of the chute or holder for the cards or envelopes; and Fig. 14 shows a modification 60 in the construction and arrangement of

springs acting upon the secondary feed device.

The broad features of the invention includes a support for the stack of sheets or envelopes together with means to secure their 60 removal one by one. In the present instance, envelopes are chosen as material suitable to illustrate the operation of the mechanism, and a stack of envelopes is indicated at 10 in the various figures. The stack is supported in an inclined way or chute 11, provided with upturned stiffening walls 12, best shown in Fig. 6. This support is secured to a frame plate 13 against which the stack is constantly pressed by a follower 65 plate 14 and follower arm 15 fulcrumed to plate 13 at 16, which are driven forward by the spring 17. This arrangement brings the forward envelop into contact with a primary feeding device which comprises a plunger 70 18, vertically movable in a guide slot 19 located in an upward extension of frame plate 13, as best shown in Figs. 3 and 4.

As shown in the drawings, the envelopes are stacked in an inverted position, and the broad inclined foot 20 of the plunger takes under the envelop flap when the plunger is depressed, so that the downward movement of the plunger carries with it the foremost envelop in the stack, as clearly shown 85 in Fig. 9. This movement of the plunger is effected by a cam arm 21 fulcrumed at 22 and provided with an open cam slot 23 which engages a stud 24 attached to the upper end of the plunger. A spring 25 90 tends to hold the arm 21 and plunger 18 in their upper position, shown in Fig. 1. At the end of the plunger movement, the feeding of the envelop is still incomplete, as the plunger foot 20 still abuts the forward edge 95 of the envelop and if grippers or rolls were brought into action at this point, they would seize the plunger as well. It is at this instant that the secondary feeding device completes the feed.

The secondary feeding device comprises a light frame or plate 26 hung upon pivots 27 carried by a yoke 28. The yoke has bars 29, 29 attached to its ends, and these bars together with the yoke are slidably vertically in the perforated lugs 30, 30 of frame plate 13. The parts described are normally kept elevated by springs 31, 31 attached to frame plate 13 and engaging the yoke 28. The frame 26 is provided with 110

offset projections 32, 32 adapted to engage the rear edge of the envelop. It is also equipped with a centrally located offset projection 33 which is engaged by an extension 34 upon the arm 21 whenever the latter is depressed. The frame 26 is normally forced outward by a spring 26^a shown in Fig. 2.

The operation of the secondary feeding device is shown most clearly in Figs. 9 and 10. As shown in Fig. 9, the plunger 18 has completed its movement, it having traveled the full extent of its guiding slot 19. At the instant the arm 21 contacts with projection 33, it ceases to act upon the plunger 18, as may be seen in Fig. 3. The first contact with projection 33 swings the frame 26 to the right as viewed in Fig. 9 so that it assumes a position back of the rear edge of the envelop. The continued movement of the arm 21 and frame 26 is then downward, carrying with them the envelop as shown in Fig. 10. As shown in that figure, the envelop is fed directly into the bite of a pair of rolls 34, 35, which may be of any description and used for any purpose.

To prevent the envelop from escaping the control of the feeding devices, a pair of drags comprising light leaf springs 36, 36 are attached to the stack support, and bear against the forward envelop so that its free fall cannot take place. Any mechanism or suitable connection that will move the arm 21 downward will cause the feeding of a sheet. This arm may also be operated manually and for this purpose a finger lug 21^a is provided, as shown in Fig. 6.

As shown in Fig. 7, provision is made for handling and feeding cards or envelopes of different lengths. The support 11 is fitted with sliding sides 37, 37 which are given a simultaneous movement to and from each other by means of a lever 38, pivoted at 38^a, to which the sides are connected by links 39, 39, the motion being communicated through slots 40, 40 located in the way 11. It will be noticed that this mechanism centers the stack as well as giving it proper support.

The mechanism thus far described is capable of wide and general application. Among its many possible uses is its adaptation to the typewriter, and in this connection applicant discloses further devices intended to supplement the mechanism already disclosed so as to provide for an effective coöperation of the feeding device and a typewriter.

Referring to the drawings, 41 represents the frame of a standard front strike typewriter. As best shown in Figs. 1 and 2, a pair of angle plates 42, 42 are secured to this frame, use being made of frame bolts 43, 43 for this purpose. To the plates 42, 42 are attached the standards 44, 44 united

by a cross-rail 45. Bolted at 46, 46 to the cross-rail are members 47, 47 which support the plate frame 13 and mechanism already described. Mechanism is further provided for the automatic control of the feeding device by means of the typewriter carriage. In the present instance this comprises a ratchet arm 48 fulcrumed at 22 and having a ratchet engagement with arm 21 by means of a spring pressed pawl 49. Adapted to 75 coact with this arm is an upright member 50 carrying a roller 51 and shackled to the typewriter carriage 52 at 53.

In operation, the carriage when moved to the right causes the roller 51 to wipe the 80 arm 48, the latter being moved by the carriage to the right. This movement depresses the arm 21 and effects a feeding operation in which an envelop is entered into the bite of the rollers 54, 55 of the carriage.

For the effective use of a feeding device of this character in combination with a typewriter, means should be provided for throwing the device into and out of operative position without trouble or loss of time. 90 Accordingly the mechanism described is specially mounted so that this result may be secured.

Referring to Figs. 1, 2, 6 and 7, the members 47, 47 bolted to the cross-rail 45 have 95 in their upstanding ears an arcuate slot 56, concentric with a bearing 57 in the ears in which the stack support 11, 12 may be rotated. Attached to the stack support and passing through the slots 56, 56 are clamping nuts 58, 58 by which the stack support may be locked in either the full or dotted line positions shown in Fig. 6. It will be seen that this construction permits an easy and expeditious movement of the feeding 100 device into and out of operative position. When the device is thus thrown into operative position, the arm 48 may ride over or upon the stud 50 attached to the carriage, if the carriage should happen to be in that 110 position; or the stud 50 would be on the wrong side of the arm 48 if the carriage were at the extreme right when the device was swung forward. To prevent any dis- 115 ablement from this cause, the arm 48 is provided with the ratchet connection including spring pawl 49, so that no interference between the carriage and feeding mechanism can occur.

When a feeding mechanism is used with a 120 typewriter, it is of great importance that the typewriter carriage should not be burdened with even a part of the weight of such mechanism, as every ounce of additional weight superposed on the carriage makes the entire 125 machine that more sluggish in operation. In the present invention, not only is the entire feeding mechanism mounted upon a stationary part of the typewriter, but the co-acting feeding devices operate to guide the 130

envelop as well as to move it toward the carriage rolls. As a result no auxiliary paper guide is needed to direct the envelop into the bite of the rolls. The envelop is fully controlled and has a complete edgewise feed all the way from the stack to the carriage rolls and auxiliary guides do not have to be added to the carriage. The only weight added to the carriage is that of the stud 50 which is relatively of but little account. The device therefore has the great advantage of not interfering with the regular operation of the typewriter to the slightest perceptible degree. But while the invention may possess great utility in connection with a typewriter, it is not to be limited to this particular use. The feeding mechanism herein disclosed has a wide range of usefulness; not only for the feeding of cards, envelopes and the like, but also sheets of every description, of paper, metal, or other material.

Fig. 14 shows a modification consisting in the substitution for the springs 31 that act upon the yoke 28 of coiled springs 66 surrounding bars 29.

Figs. 11, 12 and 13 illustrate means for adapting the apparatus to feed cards. The feed foot 20 of plunger 18 is, on each side of the latter, provided with opposite notches 60 in its upper and lower edges. In these notches are removably seated spring clips 61 carrying needle points 62 extending below the edge of the feed foot and rearwardly inclined or curved, as seen in Fig. 12. When the plunger descends in the feeding operation, the needle points will be carried into engagement with the leading card and move it down into engagement with the paper feed devices of the typewriting machine. On the floor of the container 11 is removably attached a spring clip 63 having at the rear an overturned resilient flange 64 that engages the rear edge of the floor and at the front a downwardly extending curtain or flange 65 which affords a guide or support for the card as it moves downward to the feed devices. Such a guide plate may also be used in connection with the feeding of envelopes.

50 I claim:

1. A sheet feeding mechanism having a support for the sheets, a roller to which the sheets are fed, a primary feeding device adapted to advance a sheet part of the required feeding distance, a secondary feeding device adapted to complete the feeding movement toward the roller, in combination with a lever for actuating successively the primary and the secondary feeding devices.
2. A sheet feeding mechanism having a support for the sheets, a primary feeding device adapted to advance a sheet edgewise part of the feeding distance, a secondary feeding device adapted to complete the edgewise feeding movement, and an actuator

directly engaging each of said devices in the feeding operation.

3. A sheet feeding mechanism having a support for the sheets, a plurality of feeding devices adapted to act upon each sheet to feed the sheets one by one, and an actuator adapted to engage and to operate alternately the respective feeding devices. 70

4. A sheet feeding mechanism having a support for the sheets, a plurality of feeding devices adapted to operate successively upon each sheet to feed the sheets one by one and a lever adapted by a single movement to directly actuate the feeding devices in a co-operative feeding movement. 75

5. A mechanism for feeding envelops comprising a support for the envelops, a feeding device adapted to engage the envelop beneath the flap, a second feeding device adapted to engage the rear edge of the envelop, and actuating means for the feeding devices. 80 85

6. In combination, a typewriter and an attachment for feeding envelops to the typewriter, the said attachment including a plurality of independently movable feeding devices adapted respectively to engage the envelop under the flap and at its rear edge and means adapted by a continuing movement to successively actuate the feeding devices. 90 95

7. In combination, a typewriter, an attachment for feeding envelops to the typewriter, the said attachment including a primary feeding device adapted to take under the flap, and a secondary feeding device engaging the rear edge of the envelop, and means whereby the said devices are controlled by the movement of the typewriter carriage. 100 105

8. In combination, the typewriter and a sheet feeding mechanism for the typewriter, the said mechanism including a plurality of feeding devices adapted to engage the sheets to feed them directly to the paper feed roll devices on the carriage, a lever for actuating said feeding devices and means for actuating said lever by a movement of the carriage. 110

9. In a feeding device for typewriters, a feeding plunger, a feeding plate, and a cam arm adapted to actuate successively the plunger and the plate to feed sheets or envelops to the typewriter carriage, substantially as described. 115 120

10. In combination, a typewriter, feeding mechanism for delivering sheets or envelops to the typewriter carriage, the entire feeding mechanism being carried by the stationary frame of the typewriter, and means whereby the power to operate the feeding mechanism is derived from the movement of the carriage. 125

11. In combination, a typewriter, feeding mechanism for delivering sheets or envelops 130

to the typewriter carriage, the entire feeding mechanism being carried by the stationary frame of the typewriter, and a projection mounted upon the carriage and adapted to control the feeding mechanism during the carriage movement.

12. In combination, a typewriter carriage, feeding mechanism stationary relative to the carriage for delivering sheets or envelopes to the carriage, an arm positioned in the path of the carriage and adapted to operate the feeding mechanism when moved in one direction by the carriage and to yield idly when moved in the reverse direction by the carriage.

13. In combination, a typewriter carriage, a stationary feeding mechanism for delivering sheets or envelopes to the carriage, and provided with a ratchet arm positioned in the path of part of the carriage and adapted to actuate the feeding mechanism upon movement of the carriage.

14. In combination, a typewriter, a mechanism for feeding envelopes to the typewriter carriage, and a support carried by the typewriter frame upon which the said mechanism is mounted, the support being swiveled so that the mechanism may be moved into and out of operative position with respect to the typewriter carriage and

means for holding the feeding device in its two set positions, comprising flat plate swivel bearings, one of the plates of each bearing having an annular slot and the other plates provided with clamping nuts, 35 adapted to positively hold the device in set positions.

15. In combination, a typewriter and a mechanism for feeding envelopes into the typewriter carriage, the said mechanism being swiveled to the typewriter frame so that it may be moved into and out of operative position with respect to the typewriter carriage and means on the carriage for actuating the feeding device when it is in operative position.

16. In combination, a typewriter, a holder for envelopes and sheets to be fed thereto, a feeding plunger adapted to take under the flap of an envelop and one or more sheet engaging needle-points detachably mounted on the plunger, curved backwardly and adapted to act on the front sheet of a stack.

In testimony whereof, I have hereunto subscribed my name.

BERT LANGLEY.
